CLAIM

The ornamental design for an adjustable track, as shown and described.

DESCRIPTION

FIG. 1 is an upper perspective view of a first embodiment of the adjustable track in accordance with the present invention;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof;

FIG. 8 is an upper perspective view of a second embodiment of the adjustable track in accordance with the present invention;

FIG. 9 is a front view of the first embodiment in an extended position;

FIG. 10 is a front view of the second embodiment in an extended position; and,

FIG. 11 is a reduced scale, environmental perspective view of the first embodiment.

The undisclosed views of the second embodiment are the same as the first except for the alternate placement of the bracket with the slots.

The broken lines showing portions of the adjustable track and the shipping container are for the purposes of illustrating environment and form no part of the claimed design.
